METER BOX AND THE LIKE

Ernest G. Johansson, Belmont, Mass., assignor
to Anchor Manufacturing Company, Boston,
Mass., a corporation of Massachusetts

Application December 22, 1942, Serial No. 469,817

9 Claims. (Cl. 220—55)

This invention relates to locks for boxes and enclosures of various kinds having closures which are hinged or otherwise movably mounted over openings in the boxes, particularly to meter boxes such as disclosed in my copending application Serial No. 425,771, filed January 6, 1942.

Other objects of the invention are to provide a lock which is simple and economical to construct, which is durable and reliable in use, which cannot be tampered with and which cannot become disassociated with the box or closure accidentally.

According to the present invention the lock comprises a latch and a fastener, the latch having an opening and the fastener extending not only through the opening in the latch but also through an opening in the closure of the box into interengagement with a part of the box. In one aspect of the invention the latch is pivoted or otherwise movably mounted on the closure and the latch opening extends to one edge of the latch to permit lateral movement of the latch away from the fastener when the fastener is loosened without detaching the fastener from the box, and means on the latch for obstructing the aforesaid lateral movement when the fastener is in locking position, the obstructing means preferably engaging the head of the fastener. In another aspect the closure opening is larger than the latch opening and the latch has a portion extending into the closure opening between the fastener and edge of the closure opening so that the latch is interlocked directly with the closure against lateral movement transversely of the axes of the openings. The latch is preferably in the form of a strap pivotally mounted on the closure of the box to swing edgewise along the face of the closure, the pin holding the strap against substantial movement away from the face of the closure. The aforesaid portion of the latch which extends into the closure opening is preferably formed by upsetting the edge of the opening in the latch throughout a substantial portion of the circumference of the opening to form an annular portion extending into the larger opening of the closure around the fastener, the offset edge also providing a countersunk seat for the head of the fastener, in which case the countersunk seat may constitute the aforesaid obstructing means engageable with the head of the fastener.

In the preferred form of the invention the strap is bent to form a loop intermediate the pivot pin and the fastener opening and the cover plate is mounted on the strap by means of a slot near one end to receive the strap, the part of the plate be-

tween the slot and the end of the plate forming a pivot in the aforesaid loop to permit the plate to swing away from the strap, thereby to uncover the fastener so that the closure may be unlocked. The free ends of the strap and plate preferably have interengaging parts for sealing the cover plate against the strap.

For the purpose of illustration a typical embodiment of the invention is shown in the accompanying drawing in which

Fig. 1 is a front elevation of a meter box constructed according to the present invention;

Fig. 2 is an enlarged view of the lock with the cover plate swung upwardly to uncover the lock;

Fig. 3 is a bottom plan view;

Fig. 4 is a view similar to Fig. 2 showing the latch swung to retracted position; and

Fig. 5 is a section on line 5—5 of Fig. 1.

The particular embodiment of the invention chosen for the purpose of illustration comprises a meter box identical with that disclosed in the aforesaid copending application. This box comprises side walls 1, a bottom wall 2, a top 3, a front wall 4, and a front closure 5 having an opening 6 for the cylindrical glass cover of a meter to project through. As disclosed in the aforesaid application the closure 5 has a portion extending up behind the front wall 4 to hold the upper part of the closure in position and the lower part of the closure is held closed by the lock hereinafter described. As shown in Fig. 5 the bottom 2 of the box has an upturned flange 6 at its forward edge which extends almost to the side wall 1, leaving just enough space for the side flanges 7 of the closure 5. At the bottom the closure is provided with a flange 8 fitting over the bottom of the box.

The aforesaid lock comprises a strap 11 pivoted to the closure by means of the pin 12 which permits the latch to swing laterally along the base of the closure between the locking position shown in Figs. 1, 2, 3 and 5 and the retracted position shown in Fig. 4. Near its lower end the strap 11 is provided with an opening 13 which, when the latch is in locking position, registers with a larger opening 14 in the closure 5. A fastener 15 in the form of a machine screw extends through the two openings and threads into an opening in the upstanding flange 6 of the box. The edge of the opening 13 is offset into the space between the fastener 15 and the edge of the opening 14 in the closure. This not only provides a countersunk seat for the head of the screw, but also provides integral means in the form of an annular flange 55 fitting into the closure opening 14 to interlock

the latch directly with the closure when the latch is drawn against the closure by the screw. As shown in Figs. 2 and 4 the opening 13 preferably extends to one edge of the strap so that the strap may be disengaged from the fastener without completely removing the fastener.

Between the pivot 12 and the fastener 15 the latch strap 11 is provided with a loop 25 for the purpose of pivotally supporting a cover plate 16. Near its upper end the cover plate is provided with a transverse slot to receive the latch strap 11 and the portion of the cover plate between its upper end and the aforesaid slot fits into the loop 25 to form the pivotal support which permits the cover plate to swing from the closed position shown in Figs. 1, 3 and 5 to the open position shown in Figs. 2 and 4. The cover plate may be provided with an indented portion 17 to accommodate the head of the fastener 15.

For the purpose of sealing the cover plate in closed position the lower ends of the latch and cover are provided with interengaging parts. As shown in the drawing the parts comprise a projection 18 on the latch extending through a slot 19 in the cover plate, the projection 18 being provided with an opening to receive the seal 20.

To unlock the box the seal 20 is first broken, the cover plate 16 is then swung from the closed position shown in Figs. 1, 3 and 5 to the open position shown in Figs. 2 and 4, the fastener 15 is then loosened sufficiently to swing the latch 11 from the locked position shown in Figs. 1, 2, 3 and 5 to the unlocked position shown in Fig. 4, and the closure may then be removed. To lock the box the operations are reversed. After the parts are locked, it is very difficult to tamper with the box. If the margin of the opening 13 in the latch did not interlock with the opening 14 in the cover in the closure 5, lateral blows on the locked latch would bend the fastener 15 from side to side, soon breaking it off. However with the interlocking arrangement above described, the latch is held rigidly against lateral movement relatively to the cover so long as the marginal portion of the opening 13 is held in the closure opening 14.

It should be understood that the present disclosure is for the purpose of illustration only and that this invention includes all modifications and equivalents which fall within the scope of the appended claims.

I claim:

1. A box comprising a closure having an opening therein, and means for holding the closure in closed position including a latch and a fastener, the latch having an opening and the fastener extending through both openings into interengagement with the box, the closure opening being larger than the latch opening and the latch having a portion extending into the closure opening between the fastener and the edge of the closure opening, whereby the latch is interlocked directly with the closure against lateral movement transversely of the axes of said openings.

2. A box comprising a closure having an opening therein, and means for holding the closure in closed position including a latch and a fastener, a pivot interconnecting the latch with the closure near one end of the latch, the latch having an opening near the other end and the fastener extending through both openings into interengagement with the box, the closure opening being larger than the latch opening and the latch having a portion extending into the closure opening between the fastener and the edge

of the closure opening, whereby the latch is interlocked directly with the closure against lateral movement transversely of the axes of said openings.

3. A box comprising a closure having an opening therein, and means for holding the closure in closed position including a latch and a fastener, the latch having an opening and the fastener extending through both openings into interengagement with the box, the closure opening being larger than the latch opening and the latch having an annular portion extending into the closure opening between the fastener and the edge of the closure opening throughout a substantial portion of the latch opening, whereby the latch is interlocked directly with the closure against lateral movement transversely of the axes of said openings.

4. A box comprising a closure having an opening therein, and means for holding the closure in closed position including a strap and a fastener, the strap having an opening and the fastener extending through both openings into interengagement with the box, the closure opening being larger than the strap opening and the edge of the strap opening being offset into the closure opening between the fastener and the edge of the closure opening throughout a substantial portion of the strap opening, the offset edge interlocking the strap with the closure and providing a countersunk seat for the head of said fastener.

5. A box comprising a closure having an opening therein, means for holding the closure in closed position including a latch and a fastener, means for movably mounting the latch on the closure, the latch having an opening and the fastener extending through both openings into interengagement with the box, the closure opening being larger than the latch opening and the latch having an annular portion extending into the closure opening between the fastener and the edge of the closure opening throughout a substantial portion of the circumference of the latch opening, and a cover movably mounted on the latch to move over said fastener when the latch and fastener are in position to hold the closure in closed position.

6. A box comprising a closure having an opening therein, means for holding the closure in closed position including a latch and a fastener, means for movably mounting the latch on the closure, the latch having an opening and the fastener extending through both openings into interengagement with the box, the closure opening being larger than the latch opening and the latch having an annular portion extending into the closure opening between the fastener and the edge of the closure opening throughout a substantial portion of the circumference of the latch opening, a cover movably mounted on the latch to move over said fastener when the latch and fastener are in position to hold the closure in closed position, and means for sealing the cover to the latch over the fastener.

7. A box comprising a closure having an opening therein, means for holding the closure in closed position including a strap and a fastener, a pin for pivoting the strap to the closure to swing edgewise along the face of the closure, the strap having an opening and the fastener extending through both openings into interengagement with the box, the closure opening being larger than the strap opening and the edge of the strap opening being offset into the closure opening between the fastener and the edge of

the closure opening throughout a substantial portion of the circumference of the strap opening, the offset edge interlocking the strap with the closure and providing a countersunk seat for the head of said fastener, the strap being bent to form a loop intermediate said pin and opening and a cover plate for covering said fastener head, the cover plate having a slot near one end to receive said strap, the part of the plate between the slot and end forming a pivot in said loop to permit the plate to swing away from the strap, the free ends of the strap and plate having interengaging parts for sealing the cover plate against the strap.

8. A box comprising a closure having an opening therein and means for holding the closure in closed position including a latch and a fastener having a head, a pivot interconnecting the latch with the closure near one end of the latch, the latch having an opening near the other end and the fastener extending through both openings into interengagement with the box, said head seating on the latch when in closed position, the latch opening extending to one edge of the

latch to permit lateral swinging of the latch away from the fastener when the fastener is loosened without detaching the fastener from the box, and means fast to the latch engaging the side of the head of the fastener for preventing said lateral swinging when the fastener is in said locking position.

9. A box comprising a closure having an opening therein and means for holding the closure in closed position including a latch and a fastener, the latch having an opening and the fastener extending through both openings into interengagement with the box, the fastener clamping the latch against the closure when in locked position, the latch opening extending to one edge of the latch to permit lateral movement of the latch away from the fastener when the fastener is loosened without detaching the fastener from the box, and means integral with the latch and projecting from the side face thereof into the opening of the closure, for obstructing said lateral movement when the fastener is in said locking position.
